UNITED STATES PATENT OFFICE.

HENRY E. WALLIS AND CHARLES T. KINGSTON, OF DETROIT, MICHIGAN.

BOILER.

Application filed March 29, 1924. Serial No. 702,827.

Our invention relates to an improvement in boilers of the vertical type, shown in the accompanying drawings and more particularly described in the following specification and claim.

One of the objects of the present invention is to construct a boiler in which both the upper and lower tube sheets are dished or are of concavo-convex formation whereby 10 they become self-supporting, eliminating the necessity of braces or of the stays necessary in boilers constructed with flat heads or tube sheets.

A further object of the invention is to relieve the tubes of the stresses resulting 15 from their marginal edges overlapping the tube sheet, necessary when the tubes are mounted in flat heads.

In the present construction the tubes are 20 bent at each end in such a manner that the ends may pass through the crown sheets or heads on a line with the radius of the head, the tubes standing at an angle to a vertical line that the gases of combustion in their 25 upward course may impinge directly against the walls of the tubes transferring the heat by convection and not by radiation as would be the case if the tubes were vertically disposed. When a volume of gas enters a vertical tube and starts upon its upward course 30 it decreases in volume as its velocity increases and having traveled upward a short distance there is only a small "core of gas",—so to speak,—in the center of each 35 tube, the heat being carried to the wall of the tube by radiation.

One object in providing a dished lower head is that it prevents mud from depositing or remaining upon the head between the 40 tubes,—the crowning shape of the head assisting greatly in keeping the latter clean, as the mud may be readily washed from the crowning head when the boiler is washed out;—a stream of water may be played 45 directly down from the upper hand-hole to the center of the lower head.

Another feature of the invention consists 50 in attaching to the underside of the upper crown sheet a central pipe or tube—closed at its upper end—extending downwardly, with its open end adjacent the lower crown sheet;—the upper end of the tube above the water level being perforated for the passage of steam from the steam space of the 55 boiler down through the pipe to a horizontal pipe connected therewith for conveying

the steam to the work, the central pipe being again perforated, at and immediately below the water level, to admit water which being away from the hot gases will be directed downwardly and out through the pipe contiguous to the lower crown sheet,—the water circulating adjacent to the latter. Surrounding the tubes and spaced from the shell of the boiler and downwardly from the water level in the boiler to a point adjacent the outer edge of the lower crown sheet 60 is a sleeve, concentrically supported within the shell of the boiler and open above and below for the circulation of the water downwardly between the sleeve and shell toward the crown sheet.

With the foregoing and other objects in view which will appear as the description proceeds the invention further resides in the 75 details of construction hereinafter described and claimed it being understood that changes may be made in the precise embodiment of the invention herein disclosed without departing from the spirit of the same.

In the drawings accompanying this specification:

Figure 1 is a front elevation of a boiler embodying our invention.

Figure 2 is a vertical cross-sectional view 85 of the same.

Figure 3 is a horizontal sectional view taken through the upper crown sheet.

Referring now to the letters of reference placed upon the drawings:

A denotes the outer shell of the boiler provided with hand openings A¹ and A², through which access may be gained for cleaning.

B indicates the smoke box hinged at C, 95 that access may be gained to the interior for cleaning or repairs.

D designates a fire box and E, the grate bars.

F represents a lower tube sheet of concavo-convex formation riveted to the wall of the fire box.

G denotes the upper tube sheet also of concavo-convex formation riveted to the outer shell of the boiler.

H indicates a plurality of tubes bent adjacent each end that they may enter the crown or tube-sheets on a line with the radius of the respective sheets and while the ends of the tubes may overlap the crown sheets 110 we prefer that they be flush or substantially flush with the outer surface.

- I designates a central pipe extending downwardly from a fitting riveted to the upper tube sheets provided with a plurality of apertures J, at and below the water level 5 of the boiler to admit the water into the pipe that it may be directed downwardly and out through its open end adjacent the lower tube sheet. The pipe I, is also provided with a closure plug K at its upper end and with a plurality of apertures L directly below the upper tube sheet through which steam is admitted to the central pipe for delivery through a horizontal pipe M to an engine or other device—not shown.
- 15 N, denotes a sleeve surrounding the tubes H and spaced from the shell of the boiler, extending from a point at or near the water level of the boiler downwardly toward the lower tube sheet that the water may circulate downwardly between the sleeve and outer shell and adjacent the lower tube sheet—as indicated by the arrows in Figure 2.

Having now designated the several parts 25 by reference letters the construction and operation of the boiler will be readily understood.

As previously pointed out the "crowning-shape" of the upper and lower tube sheets 30 eliminates the necessity of employing the usual braces and stays required in constructing boilers having flat heads for the support of the tubes, and it also relieves the tubes of all strain resulting from their ends being flanged to overlap the tube sheets or heads. So also the tubes being bent adjacent their ends makes it practical to insert the ends on the radius of the respective heads. The bent ends of the tubes also provide 35 for the expansion of the tubes, and that the tubes may be inclined slightly in order that the gases in their passage therethrough may impinge upon the walls of the tubes transferring the heat by convection to the 40 surrounding body of water. The "crowning" formation of the lower head materially

assists in preventing the deposit of mud that would result if the tube sheet were flat and assists in freeing the head should any deposit occur. The central tube and inner 50 sleeve provide means for the circulation of water downwardly toward the lower crown sheet, as will be readily understood. The hinged construction of the smoke box and the upper and lower hand-hole plates provide 55 means whereby the boiler may be readily cleaned or repaired. The arched construction of the upper crown sheet materially adds to the steam space of the boiler at a given water level.

Having thus described our invention, we claim:

In a vertical tube boiler, upper and lower tube sheets, a plurality of tubes connected to the tube sheets, a central pipe extending 60 through the upper tube sheet and suspended therefrom and terminating immediately above the same, a plug to close the upper end of said central pipe and the latter extending downwardly from the upper tube sheet to a point adjacent the lower tube sheet and open 65 at its lower end and having a plurality of apertures adjacent the water level, whereby the water in the boiler may circulate 70 downwardly through said pipe and be discharged therefrom adjacent the lower tube sheet, a horizontally disposed pipe disposed below the upper tube sheet and connected with the said central pipe and extending through the shell of the boiler between the 75 tubes for the passage of steam, said central pipe having a plurality of apertures above 80 said horizontally disposed pipe below the upper tube sheet open to the steam space of the boiler, whereby steam may be admitted 85 in the said central pipe for passage through said horizontal pipe.

In testimony whereof, we sign this specification.

HENRY E. WALLIS.
CHAS. T. KINGSTON.
